UNITED STATES PATENT OFFICE.

ISAAC J. VINCENT, OF PITTSTON, PENNSYLVANIA, ASSIGNOR TO THE UNION STOVE AND MANUFACTURING COMPANY, OF SAME PLACE.

DESIGN FOR A COOKING-STOVE.

Specification forming part of Design No. 6,240, dated November 5, 1872.

To all whom it may concern:

Be it known that I, I. J. VINCENT, of Pittston, in the county of Luzerne and State of Pennsylvania, have invented a new and original Design for a Stove called the "Favorite," of which the following is a specification:

The accompanying photograph fully illustrates my new design.

This invention relates to a new design for a cooking-stove. It consists, first, in ornamenting the stove-legs with rectangular projecting panels, as shown; also, in the design for the moldings of the doors of the stove, which are combined with inner rows of beading; also, in

the new design of center ornament of the oven-door, which is composed of scrolls that embrace a symmetrical shield, as shown.

Having thus described my invention, I claim as new and desire to secure by Letters Patent—

1. The design for the stove-legs, as shown.
2. The design for the moldings of the stove-doors, as shown.
3. The design for the panel ornament of the oven-door, as shown.
